[57] CLAIM

The ornamental design for a rehabilitation therapy board, as shown and described.

DESCRIPTION

FIG. 1 is a perspective view of a rehabilitation therapy board, showing my new design;

FIG. 2 is a top plan view thereof;

FIG. 3 is an elevational view as seen looking down from the top of FIG. 2;

FIG. 4 is an elevational view as seen looking to the left from the right of FIG. 2.

The bottom is flat and unornamented.
